UNITED STATES PATENT OFFICE

2,075,601

HEATING OF FLUIDS

Marion W. Barnes, Chicago, Ill., assignor to Universal Oil Products Company, Chicago, Ill., a corporation of Delaware

Application June 7, 1934, Serial No. 729,364

13 Claims. (Cl. 196—116)

This invention particularly refers to an improved method and means of heating fluids such as hydrocarbon oils to the high temperatures required for their conversion and more particularly refers to improvements in the type of furnace wherein separate combustion zones are employed; heat derived from one zone, primarily by radiation, being utilized to quickly heat the oil to the desired conversion temperature while heat derived from the other combustion zone, also primarily by radiation, is utilized to maintain the oil at a fairly constant conversion temperature for a predetermined time and combustion gases from both combustion zones being utilized to heat the incoming oil to a temperature below the desired conversion temperature attained by the oil in the first mentioned combustion zone. —

One of the principal problems in the design of furnaces of the character above described, where in the oil is first heated to the desired conversion temperature and then maintained at or near the attained temperature for a predetermined time, has been the large drop in pressure due to friction through the fluid conduit, which is necessarily of unusual length due to the time element required in the soaking section, i. e. that section wherein the oil is maintained at a fairly constant temperature for a predetermined time. This necessitates exceptionally high pressures in the first heating stages in order to maintain the desired conversion pressure in the soaking section and obviously greatly increases pumping costs as well as necessitating the use of thicker wall tubes and fittings to maintain the proper safety factor and obviate unusual fire and explosion hazard. An increase in the diameter of the fluid conduit for the purpose of reducing the pressure drop for a given volume of oil flowing therethrough, due to friction, greatly reduces the effectiveness of the heating surface measured over a given tube area, since the cross-sectional area, which determines the volume of the tube, increases out of proportion to the increased circumference, which determines the heating surface. Therefore, the heating surface per unit volume of oil undergoing treatment is decreased by increasing the tube diameter.

In the present invention in order to maintain the desired ratio of heating surface to tube volume or volume of oil undergoing treatment without an excessive pressure drop, due to friction through the fluid conduit, the stream of oil during its passage through a major portion, at least, of the fluid conduit is divided into a plurality of

substantially equal streams, parallel rows of tubes of the usual size being employed for the various streams.

In that portion of the fluid conduit subjected to heating by contact with combustion gases from both combustion zones of the furnace, wherein the incoming oil is heated to below conversion temperature or to a relatively mild conversion temperature, the total volume of oil supplied to the furnace may be split into two or more streams of substantially equal volume each of which is passed simultaneously and in series through an equal number of tubes comprising similar portions of said fluid conduit, each of said similar portions being subjected to substantially the same heating conditions.

That portion of the fluid conduit wherein the oil is brought to or near the desired maximum conversion temperature may comprise, for example, a single horizontal row of horizontally disposed tubes located along the floor of one combustion zone of the furnace and a single horizontal row of horizontally disposed tubes located along the roof of the same combustion zone. In accordance with the present invention, the total volume of oil having passed through the previously mentioned portion of the fluid conduit, to which the incoming charging stock is supplied, may be split into two streams of substantially equal volume, one of which is passed in series through adjacent tubes comprising said row of tubes along the floor of the combustion zone while the other stream is passed in series through adjacent tubes comprising said row of tubes along the roof of the combustion zone. Since the row of tubes adjacent the floor of the combustion zone is normally exposed to more severe heating conditions than the row of tubes adjacent the roof of the combustion zone the stream of oil supplied to the roof bank is preferably passed through a greater number of tubes in this bank than those employed for heating the other stream of oil in the floor bank, and/or, when desired, a somewhat greater volume of oil may be supplied to the floor tubes than to the roof tubes. Furthermore, in order to insure that both streams of oil from this portion of the fluid conduit enter the soaking section of the furnace at the same temperature I preferably commingle the two streams and pass the commingled stream in series through several tubes located adjacent the roof of the furnace, prior to its introduction into the soaking section.

In the preferred embodiment of the present invention, that portion of the fluid conduit wherein

the highly heated hydrocarbon oil is maintained for a predetermined time at a temperature near the maximum conversion temperature previously attained preferably comprises parallel shielded and exposed horizontal rows of horizontally disposed tubes located adjacent the roof of the other combustion zone of the furnace and parallel exposed and shielded horizontal rows of horizontally disposed tubes located adjacent the floor of said 10 combustion zone. In accordance with the invention, in order to minimize friction and pressure drop through this portion of the fluid conduit and in order to uniformly heat the total volume of oil supplied therethrough, the highly heated oil entering this portion of the fluid conduit is preferably split into two streams of substantially equal volume each of which is passed through an equal number of exposed and shielded tubes. This may be accomplished, for example, 15 by employing a criss-cross flow through the shielded and exposed rows of tubes, each of the two streams passing, for example, first through a tube in the exposed row and then through a tube in the shielded row of the roof bank, then through another tube in the exposed row and so on 20 throughout the length of the two rows of tubes adjacent the roof and floor of the combustion zones; different streams of oil flowing through adjacent tubes in each row and the number of shielded tubes and exposed tubes in each row being 25 equal. In this manner regardless of different heating conditions in the exposed and shielded rows and even though heating conditions may vary in different portions of the same row substantially equal heating is obtained in both 30 streams and, due to equal heating and equal friction in each stream, a substantially equal quantity of oil may be maintained in each stream. 35

In one embodiment, the invention comprises 40 dividing a stream of hydrocarbon oil to be subjected to conversion into a plurality of substantially equal streams, passing each stream simultaneously and in series through an equal number of tubes in similar sections of a fluid conduit, each 45 section being subjected to substantially equal heating conditions by contact with commingled hot combustion gases from two separately fired combustion and heating zones of a furnace, whereby each stream of oil is subjected to substantially 50 equal heating conditions, then passing the heated oil in two streams of substantially equal volume through a fluid conduit comprising rows of tubes located adjacent the roof and floor of one combustion zone of the furnace, one stream 55 of oil passing in series through the tubes adjacent the floor and the other stream of oil passing in series through the tubes adjacent the roof, whereby each stream is subjected to substantially equal heating conditions by predominantly radiant heat 60 from materials undergoing combustion in said combustion zone and hot refractory walls of the furnace and whereby the total oil is brought to near the maximum desired conversion temperature, then commingling the two streams of highly 65 heated oil and passing the same through a plurality of tubes located adjacent the roof of the furnace whereby the temperature of the two streams is equalized, then dividing the stream of highly heated oil into two streams of substantially 70 equal volume and passing the same in series through tubes comprising shielded and exposed rows of tubes located adjacent the roof and floor of the other combustion zone in such a manner that each stream is passed through an equal number of shielded and exposed tubes, whereby each 75

stream is subjected to substantially equal heating conditions by primarily radiant heat from materials undergoing combustion in said combustion zone and the hot refractory walls of the furnace; the heating in the last mentioned combustion zone being of sufficient intensity to maintain the oil at a substantially uniform temperature approaching the maximum to which it is subjected during its passage through the fluid conduits in this portion of the furnace. 5

The accompanying diagrammatic drawing is a sectional elevation in cross-section of one specific form of furnace embodying the various features of the present invention and in which the process of the invention and the desired results may be 10 15 accomplished. 15

Referring to the drawing, the outer walls of the furnace are indicated at 1 and comprise the usual side walls, end-walls, roof and floor of any desired standard construction. The interior of the 20 furnace comprises two combustion zones designated, respectively, as 2 and 3 and a convection heating zone 4, which latter is separated from the combustion zones 2 and 3 by the respective bridge walls 5 and 6. 25

Fuel is supplied by means of any suitable form of burners 23 through one or, preferably, a plurality of firing tunnels 7 to each of the combustion zones 2 and 3. Any suitable fuel such as oil, gas or pulverized solid fuel being supplied, together with a portion of the air required for combustion, through the central portions or combustion compartments 8 of the tunnels while the desired auxiliary air is supplied to the combustion zone through tunnels 9 and 10 adjacent the central tunnel 8 and regulated by means of suitable dampers 11. The air admitted through tunnels 9 and 10 commingles with the fuel and air undergoing combustion from tunnel 8, assisting in controlling the combustion conditions and particularly the character of the flame in combustion zones 2 and 3 of the furnace. 30 35 40

The materials undergoing combustion in zones 2 and 3 of the furnace give up a major portion of their radiant energy to the fluid conduit located along the floor and roof of the combustion zone, as will be later more fully described, by means of which predominantly radiant heat is transmitted to the oil passing through the fluid conduit. The combustion gases pass from combustion zones 2 and 3 over the bridge walls 5 and 6, respectively, and pass thence downward through the so-called convection heating zone 4 of the furnace where they give up heat largely by convection, although to some extent by radiation, to the fluid conduit in this portion of the furnace and to the oil passing therethrough. The spent combustion gases pass from convection zone 4 through flue 12 to a stack (not shown). 45 50 55

A bank 13 of horizontally disposed tubes 14 arranged in horizontally parallel rows is located in convection zone 4 of the furnace and, in the particular case here illustrated, is divided into eight similar vertical sections through each of which a separate stream of oil is passed, each stream being of substantially equal volume. Adjacent tubes in each vertical section of bank 13 are connected in series at their ends by means of suitable headers or return bends (not shown) preferably located outside the heating zone. The stream of oil to be subjected to heating and conversion is supplied to the furnace from any suitable source in a single stream indicated in the drawing by lines 15 and 16. This stream is then split into two substantially equal streams, one designated as 15 and 70 75

the other as 16, controlled by the respective valves 15' and 16', each of which are again split, as indicated in the drawing, into two substantially equal streams and then four substantially equal streams 5 so that eight substantially equal streams of oil now through the eight similar sections of tube bank 13. The eight streams of oil having passed through bank 13 are recombined to form two substantially equal streams again designated as 15 10 and 16. The single lines 15 and 16 throughout the drawing indicate substantially equal streams of oil. The dotted portions of these lines designate connections between adjacent tubes and between different portions of the fluid conduit on the far 15 side of the furnace and the solid portions indicate the connections on the near side of the furnace. The arrows on these lines indicate the general direction of flow in each stream.

A single horizontal row 17 of horizontally disposed tubes 14 is located along the floor of combustion zone 2. Preferably, as illustrated, this tube bank is depressed somewhat below the outlet from firing tunnel 7 so that it is out of the direct path of the materials undergoing combustion 25 from this zone. The stream 15 from tube bank 13 is passed in series through adjacent tubes of bank 17, flowing, in the case here illustrated, in a general direction counter-current to the direction of firing.

30 A single horizontal row 18 of horizontally disposed tubes 14 is located along the roof of the furnace above combustion zone 2 and convection zone 4. The stream 16 from tube bank 13 passes in series through adjacent tubes in the major portion 35 18' of tube bank 18 in a general direction counter-current to the direction of firing in combustion zone 2 and then commingles in the remaining tubes of bank 18, comprising the section of this bank designated in the drawing as 18'', with stream 15 from tube bank 17, the commingled streams flowing in series through adjacent tubes of section 18'' to subsequent portions of the fluid conduit which will be presently described.

40 The oil passing through banks 17 and 18 is heated, primarily by radiation from the combustion gases and hot refractory walls of the furnace, to or near the maximum conversion temperature to which it is desired to subject the oil and, preferably, relatively high rates of heating are employed in this portion of the fluid conduit so that the oil is brought quickly to the desired temperature.

45 Two parallel horizontal rows 19 and 20 of tubes 14 comprise that portion of the soaking section of the fluid conduit located adjacent the roof of combustion zone 3. The commingled streams 15 and 16 from section 18'' of the fluid conduit are again split into two substantially equal streams designated as 15'' and 16'', stream 15'' entering the end tube of bank 20 and stream 16'' entering the adjacent tube of the same bank. The respective streams then pass in parallel through adjacent tubes in shielded row 19, thence through the next 50 two adjacent tubes in exposed row 20 and so on throughout this portion of the fluid conduit.

55 Parallel horizontal rows 21 and 22 of tubes 14 comprise the remainder of the soaking section of the fluid conduit and are located adjacent the floor of combustion zone 3. As in the case of floor bank 17, these tubes are preferably depressed somewhat below the outlet from the firing tunnel to remove them from the direct path of the materials undergoing combustion. The two streams of oil 15'' and 16'' from banks 19 and 20 flow through the

tubes in the shielded and exposed rows 21 and 22, respectively, of the floor bank in a manner similar to that described, in connection with rows 19 and 20 of the roof bank. The two streams again commingle in the final shielded tube 14' of the 5 floor bank from which the single stream, designated as 15''' and 16''', of heated oil is discharged to any desired further stage of the cracking process.

60 It will be noted that the two substantially equal streams 15''' and 16''' are subjected to substantially equal heating conditions in the soaking section of the fluid conduit comprising shielded rows 19 and 21 and exposed rows 20 and 22 in combustion zone 3. The two streams flow in 15 parallel through adjacent tubes in both the shielded and exposed rows insuring that any unequal heating conditions in different zones along the heating coil will not produce different heating conditions in the two streams; furthermore, 20 the number of shielded tubes in each stream is equal to the number of shielded tubes in the other stream and the number of exposed tubes in each stream is equal to the number of exposed tubes in the other stream, obviating any inequality in 25 the heating of the two streams, due to different heating conditions in the shielded and exposed rows of tubes.

30 Preferably relatively mild heating conditions are employed in combustion zone 3 sufficient only to maintain the oil flowing through the fluid conduit in this zone at a substantially constant temperature near the maximum temperature attained in the preceding portion of the fluid conduit.

35 It will be understood that various modifications of the specific form of apparatus illustrated and the specific flow above described may be employed without departing from the scope of the invention. For example, a fewer number of parallel streams may be employed, when desired, in bank 13, also, when desired, the general direction of flow of the oil through this zone may be concurrent to the flow of combustion gases instead of counter-current. Furthermore, the direction 40 of flow of oil through either or both of tube banks 17 and 18 may be reversed, when desired. Valves 15' and 16' in streams 15 and 16, respectively, permit variations in the quantity of oil supplied through each of these streams, when desired, in order to insure a substantially equal temperature 45 in each stream as they enter the soaking portion of the fluid conduit and it is within the scope of the present invention, when desired, to use section 18'' of bank 18 for heating either stream 50 15 or 16 to the exclusion of the other stream. It is also specifically within the scope of the present invention, when desired, to omit the tubes in rows 18, 19 and 20 which are located above and opposite to the tubes in bank 13. When these tubes are omitted a higher proportion of radiant heat will be imparted to the tubes in the upper rows 55 of bank 13 and consequently a somewhat higher rate of heating will be obtained in this portion 60 of the fluid conduit.

65 I claim as my invention:

70 1. A furnace for heating fluids which comprises, in combination, two combustion zones, means for independently controlling the heating conditions in each combustion zone, a convection zone, means for supplying combustion gases from both combustion zones to the convection zone, a plurality of elongated tubular elements located within the convection zone, 75

means for heating said elements by heat from the combustion gases, a plurality of elongated tubular elements located adjacent the roof of each combustion zone and heated predominantly by radiant heat, a plurality of elongated tubular elements located adjacent the floor of each combustion zone and heated predominantly by radiant heat, means for passing fluid to be heated in a plurality of separate streams of substantially equal volume through the tubular elements in the convection zone, means for passing separate portions of the fluid undergoing treatment in two separate substantially equal streams through the tubular elements located, respectively, adjacent the floor and adjacent the roof of one combustion zone, means for passing the fluid undergoing treatment in two separate substantially equal streams through the tubular conduits located adjacent the roof and floor of the other combustion zone.

2. A furnace for heating fluids which comprises, in combination, two combustion zones, means for independently controlling the heating conditions in each combustion zone, a convection zone, means for supplying combustion gases from both combustion zones to the convection zone, a fluid conduit comprising a plurality of elongated tubular elements located within the convection zone, means for heating said fluid conduit by heat from the combustion gases, a fluid conduit comprising a single row of elongated tubular elements located adjacent the floor of one combustion zone, a fluid conduit comprising a single row of elongated tubular elements located adjacent the roof of the same combustion zone, a shielded row and an exposed row of elongated tubular elements located adjacent the roof and adjacent the floor of the other combustion zone, means for passing the fluid to be heated in a plurality of substantially equal streams through similar portions of the fluid conduit located within the convection zone, each of said sections being subjected to substantially equal heating conditions, means for then passing the fluid in two substantially equal streams through the fluid conduits located adjacent the roof and floor of the first mentioned combustion zone, one stream flowing through the row of tubes adjacent the roof and the other stream flowing through the row of tubes adjacent the floor, each stream being heated to substantially the same temperature and means for then passing the fluid in two substantially equal streams through said shielded and exposed rows located adjacent the roof and floor of the other combustion zone, each stream flowing through an equal number of exposed tubes and each stream flowing through an equal number of shielded tubes whereby the two streams are subjected to substantially equal heating conditions in this zone.

3. A furnace for heating fluids which comprises, in combination, two combustion zones, means for independently controlling the heating conditions in each combustion zone, a convection zone, means for supplying combustion gases from both combustion zones to the convection zone, a fluid conduit comprising a plurality of elongated tubular elements located within the convection zone, means for heating said fluid conduit by heat from the combustion gases, a fluid conduit comprising a single row of elongated tubular elements located adjacent the floor of one combustion zone, a fluid conduit comprising a single row of elongated tubular elements located adjacent the floor of the other combustion zone, means for then passing the fluid in two substantially equal streams through the fluid conduits located adjacent the roof and floor of the first mentioned combustion zone, one stream flowing through the row of tubes adjacent the roof and the other stream flowing through the row of tubes adjacent the floor, each stream being heated to substantially the same temperature and means for then passing the fluid in two substantially equal streams through said shielded and exposed rows located adjacent the roof and floor of the other combustion zone, each stream flowing through an equal number of exposed tubes and each stream flowing through an equal number of shielded tubes whereby the two streams are subjected to substantially equal heating conditions in this zone.

elements located adjacent the roof of the same combustion zone, a shielded row and an exposed row of elongated tubular elements located adjacent the roof and adjacent the floor of the other combustion zone, means for passing the fluid to be heated in a plurality of substantially equal streams through similar portions of the fluid conduit located within the convection zone, each of said sections being subjected to substantially equal heating conditions, means for then passing the fluid in two substantially equal streams through the fluid conduits located adjacent the roof and floor of the first mentioned combustion zone, one stream flowing through the row of tubes adjacent the roof and the other stream flowing through the row of tubes adjacent the floor, means for commingling the stream of fluid having passed through the row of tubes adjacent the floor with the stream of fluid passing through the row of tubes adjacent the roof in at least one tube of said row adjacent the roof and means for then passing the fluid in two substantially equal streams through said shielded and exposed rows located adjacent the roof and floor of the other combustion zone, each stream flowing through an equal number of exposed tubes and each stream flowing through an equal number of shielded tubes, whereby the two streams are subjected to substantially equal heating conditions in this zone.

4. A furnace for heating fluids which comprises, in combination, two combustion zones, means for independently controlling the heating conditions in each combustion zone, a convection zone, means for supplying combustion gases from both combustion zones to the convection zone, a fluid conduit comprising a plurality of elongated tubular elements located within the convection zone, means for heating said fluid conduit by heat from the combustion gases, a fluid conduit comprising a single row of elongated tubular elements located adjacent the floor of one combustion zone, a fluid conduit comprising a single row of elongated tubular elements located adjacent the roof of the same combustion zone, a shielded row and an exposed row of elongated tubular elements located adjacent the roof and adjacent the floor of the other combustion zone, means for passing the fluid to be heated in a plurality of substantially equal streams through similar portions of the fluid conduit located within the convection zone, each of said sections being subjected to substantially equal heating conditions, means for then passing the fluid in two substantially equal streams through the fluid conduits located adjacent the roof and floor of the first mentioned combustion zone, one stream flowing through the row of tubes adjacent the roof and the other stream flowing through the row of tubes adjacent the floor, means for commingling the stream of fluid having passed through the row of tubes adjacent the floor with the stream of fluid passing through the row of tubes adjacent the roof in at least one tube of said row adjacent the roof and means for then passing the fluid in two substantially equal streams through said shielded and exposed rows located adjacent the roof and floor of the other combustion zone, each stream flowing through an equal number of exposed tubes, each stream flowing through an equal number of shielded tubes and the two streams flowing in parallel through adjacent tubes in the shielded row and adjacent tubes in the exposed row.

5. In a process for the pyrolytic conversion of relatively low boiling hydrocarbon oils, the method of heating which comprises dividing a stream of said oil into a plurality of substantially equal streams, passing each of said substantially equal streams simultaneously through an equal number of tubes in similar sections of a fluid conduit, each section being subjected to substantially equal heating conditions by contact with streams through the tubes in the convection zone, means for passing a portion of the thus heated fluid through said floor tubes and another portion thereof through said roof tubes, and means for then passing the fluid in separate streams through said additional tubes. 5
9. In a furnace having a combustion zone and a convection zone adapted to receive combustion gases from the combustion zone, the combination of a plurality of banks of heating tubes so arranged in the convection zone as to be substantially uniformly heated by said gases, a row of serially connected floor tubes and a row of serially connected roof tubes in the combustion zone, means for passing fluid to be heated in a plurality of parallel streams through the banks of tubes in the convection zone, and means for passing some of said streams in admixture through said floor tubes and for passing others thereof in admixture through said roof tubes. 10 15 20
10. In a furnace having a pair of independently fired combustion zones, the combination of a row of serially connected floor tubes and a row of serially connected roof tubes in one of said zones, additional tubes in the other of said zones, means for passing a stream of fluid to be heated through said row of floor tubes and another stream thereof through the row of roof tubes and for then combining the separate streams, and means for passing the thus heated fluid through tubes in said other zone. 25 30
11. In a furnace having a pair of independently fired combustion zones, the combination of a row of serially connected floor tubes and a row of serially connected roof tubes in one of said zones, two series of tubes in the other of said zones, means for passing a stream of fluid to be heated through said row of floor tubes and another stream thereof through the row of roof tubes and for then combining the separate streams, and means for passing a separate portion of the resultant mixture through each series of tubes in said other zone. 35 40
12. In the subjection of hydrocarbon oils to conversion temperatures in a furnace having a pair of independently fired combustion and radiant heat zones, the method which comprises passing a stream of oil adjacent the floor and another stream adjacent the roof of one of said zones, then combining the streams and dividing the resultant mixture into separate portions, and subjecting these portions to substantially equal heating conditions in the other of said zones. 45 50
13. In the subjection of hydrocarbon oils to conversion temperatures in a furnace having a pair of independently fired combustion and radiant heat zones and a convection zone receiving combustion gases from both said combustion zones, the method which comprises uniformly heating separate streams of the oil in the convection zone, passing some of said streams in admixture adjacent the floor of one of said combustion zones, passing others of said streams in admixture adjacent the roof of the same combustion zone, and then subjecting all portions of the oil to substantially uniform heating conditions in the other of said combustion zones. 55 60 65
40. 8. A furnace for heating fluids comprising a pair of combustion zones and a convection zone, means for passing combustion gases from both said combustion zones through the convection zone, a plurality of heating tubes in the convection zone, a row of serially connected floor tubes and a row of serially connected roof tubes in one of said combustion zones, additional heating tubes in the other of said combustion zones, means for passing the fluid to be heated in a plurality of streams through the tubes in the convection zone, means for passing a portion of the thus heated fluid through said floor tubes and another portion thereof through said roof tubes, and means for then passing the fluid through said additional tubes. 55
45. 9. A furnace for heating fluids comprising a pair of combustion zones and a convection zone, means for passing combustion gases from both said combustion zones through the convection zone, a plurality of heating tubes in the convection zone, a row of serially connected floor tubes and a row of serially connected roof tubes in one of said combustion zones, additional heating tubes in the other of said combustion zones, means for passing the fluid to be heated in a plurality of streams through the tubes in the convection zone, passing some of said streams in admixture adjacent the floor of one of said combustion zones, passing others of said streams in admixture adjacent the roof of the same combustion zone, and then subjecting all portions of the oil to substantially uniform heating conditions in the other of said combustion zones. 60 65
